UNITED STATES PATENT OFFICE.

GEORGE W. ABRAHAM, OF DETROIT, MICHIGAN.

SHOT LOADER.

Application filed December 15, 1926. Serial No. 154,915.

This invention relates to shot loading devices for rifles or the like, and has for its object the provision of a tubular loading device having a discharge spout specially constructed to prevent jamming of the shot as the same pass therethrough.

Another object of the invention is to provide a simple and inexpensive means for closing the spout of the loader.

Another object of the invention is to provide a novel closure for the filling end of the loader.

Other objects will appear hereinafter.

In the drawing,

Figure 1 is a view of a rifle magazine in the process of being filled by the loader;

Fig. 2 is an enlarged longitudinal sectional view of a rifle barrel and magazine enclosed therein;

Fig. 3 is an enlarged sectional fragmentary view of the loader illustrating the construction of the spout of the loader, and

Fig. 4 is an enlarged part sectional view of the loader, illustrating the spring for closing the spout, and the snapping cap for closing the filling end of the loader.

Like characters of reference of the drawing designate corresponding parts.

Referring to the drawing:

A rectilinear sheet of metal, cardboard, fibre board, or the like, is rolled to form a tube 10. The side of one end of the tube preferably, at the point where the ends of the sheet abut one another, is pressed in, thus forming a crimp 11, which reduces the diameter of the tube to a restricted orifice 12 of a diameter permitting the discharge of but one shot at a time. The spout thus formed is provided with a hole 13; and a wire 14 secured to the body of tube by one or more turns 9, is so shaped as to enter said hole of the spout, and provide a convenient dispensing closure for the spout capable of easy manipulation by the thumb of an operator.

The opposite end of the tube is left rough finished, thus having a somewhat expanded end, as indicated at 15 in the drawing, and a snap cap 16 is provided which is a cup like stamping having the margin of the skirt portion thereof slightly flared out, as indicated at 17 to permit the cap to receive the rough end of the tube, whereby the resiliency of the cap may be utilized to hold the same in position.

The wall of the tube at the dispensing end

with one or more indentations 18 in order to prevent jamming of the shot at the spout.

The magazine 19 with which this invention is adapted to be used, has generally a filling hole 20, and is constructed to fit the rifle barrel 21.

In operation, with the magazine in the left hand and the loader tube in the right hand, as illustrated in Fig. 1, and with the thumb of the right hand manipulating the wire 14, shot is poured into the interior of the magazine, and what is generally, by its very nature, a tedious operation is thus made easy and certain. Jamming of the shot is positively checked by the indentations 18 in the wall of the tube. The snap cap 16 serves as an effective closure for the filling end, and by the exertion of a small pressure, the cap is easily removed for refilling the loader.

From the foregoing it will be seen that there is provided a most simple, efficient and inexpensive loader for rifles employing shot.

Modification of the above may be made within the spirit and scope of the invention.

What I claim is:

1. A shot loading device including a tube having a crimp in one end forming a restricted orifice of a size to discharge a single shot at a time, an indentation at said crimped portion for preventing jamming of shot at said orifice, and removable means for obstructing said orifice.

2. In a shot loading device, the combination of a tube, having a crimp in the side of one end to form an orifice adapted to discharge a single shot at a time, said crimp formed with adjacent indentations to prevent jamming of shot at said orifice; and a spring arranged across the orifice of the stem, being normally urged into the tube for obstructing the passage of the shot therethrough.

3. A shot loading device including a tube having a restricted orifice at the dispensing end of a size to discharge a single shot at a time, a wire extending across said orifice resiliently held in position for controlling the discharge, and a cap for the opposite end of said stem having a flaring skirt portion adapted to coat with the sheared surface of the tube end to provide a yieldable locking engagement therewith.

4. A tube for loading shot having one end laterally crimped to provide a restricted discharge orifice, the wall of the tube under

2. said crimp formed with adjoining internal indentations to prevent more than one shot at a time from resting upon the shot immediately behind the leading shot, and wire 5 means for closing said orifice providing easy manipulation during the dispensing operation.
3. A shot loading tube having the side at one end squeezed in to form a spout, indentations formed in the wall adjacent said crimp whereby jamming of the shot is prevented; a wire for holding the shot within said tube, and a cap having a slightly expanded skirt adapted to resiliently engage 10 with the sheared end of the opposite end of said tube and form a removable closure therefor.
6. In combination, a tube having its wall crimped at one end to provide a restricted passage, and a hole in the wall near the end 20 of the tube; a wire having one or more fastening turns, about said tube, and a hooked end for engagement within said hole for closing said passage, and a spring cap adapted to engage the sheared surface of the opposite end of the tube to provide a removable closure therefor. 25

In testimony whereof I affix my signature.

GEORGE W. ABRAHAM.
